UNITED STATES PATENT OFFICE

EDGAR HEATON, OF BREMERTON, WASHINGTON

AUXILIARY ATOMIZER FOR INTERNAL-COMBUSTION ENGINES

Application filed July 16, 1926. Serial No. 122,926.

This invention relates to auxiliary atomizers for internal combustion engines and more particularly to a device of this character adapted to be attached to the intake valve 5 of the engine.

A further object of the invention is to provide a device of this character which will not interfere with the flow of the atomized fuel to the cylinders of the engine and which 10 will tend to thoroughly break up any unatomized particles of fuel which are entering the cylinder.

A further object of the invention is to provide a device attached to the stem of the ordinary poppet valve of an internal combustion engine and operating in the port, which the poppet valve closes, which substantially bridges the port and which is so formed that unatomized particles of fuel coming into contact therewith are broken up before their 20 entry into the cylinder.

These and other objects I attain by the construction shown in the accompanying drawings, wherein for the purpose of illustration 25 is shown a preferred embodiment of my invention and wherein:—

Figure 1 is a vertical sectional view through a portion of an internal combustion engine having a poppet valve embodying an atomizer 30 constructed in accordance with my invention;

Figure 2 is a section through the poppet valve stem looking down upon the atomizer;

Figure 3 is a sectional view showing a further method of attaching the atomizer 35 to the poppet valve stem.

Referring now more particularly to the drawings, the numeral 10 generally designates a poppet valve of an internal combustion engine opening into a cylinder or combustion space 11 to admit fuel therein. This valve, as in the usual engine construction, co-acts with a seat 12 formed at the inner end of a port 13 connecting the combustion space 11 with a gas inlet space 14 to which gas is 40 introduced from the carburetor (not herein shown). The port 13 is usually formed by counterboring the wall 15, separating the combustion space from the gas inlet space and accordingly the walls of this port are 45 usually straight and concentric with the stem

16 of the valve. This stem operates within a guide 17 formed in the opposite wall 18 of the gas inlet space and is accordingly held against transverse movement.

In accordance with my invention, I secure 55 to the stem of the valve, either integrally as shown at 19 in Figure 1 or by means of a set-screw 21, as shown in Figure 3, the smaller end 22 of a bell-shaped flange 23, the diameter of which at the perimeter of the larger end 24 is substantially equal to the diameter of the bore of the port 13. This flange is 60 perforated, the number of small openings 25 preferably about one-sixteenth of an inch in diameter and arranged as closely together as 65 possible without weakening the flange. The flange is so secured to the stem 16 that the larger end of the flange just enters the lower end of the bore of the port 13 when the valve 10 is fully seated, so that the greatest possible 70 space is provided between adjacent faces of the valve and flange in which the incoming fuel, separated into small streams during its 75 passage through the openings 25, may again become homogeneous before entering the cylinder. In addition to its function of breaking up the particles of fuel entering the engine, this valve further acts to steady and prevent undue vibration of the valve, so that the valve will be much more apt to seat properly. Passage of foreign matter to the cylinders will, of course, be prevented by the screen and the screen itself will be kept clean 80 of such foreign matter, due to the jarring action to which it is subjected.

While the use of a perforated plate, such as indicated, is preferred, it will, of course, be obvious that any suitable atomizing material, capable of withstanding the vibration to which valves of this character are necessarily subjected, may be employed and I accordingly do not limit myself to the specific structure hereinbefore set forth except as hereinafter claimed.

I claim:—

An admission valve for the control of a circular inlet port of a gas engine having at one end an inclined seat surface, comprising a poppet valve adapted to engage the seat surface and having a stem fixed thereto, said 100

stem passing centrally through the port, a bell-shaped body carried upon the stem at a point spaced from the valve, the stem passing through the longitudinal center of the body, said body having a lip extended laterally forming a flat annular portion disposed in a plane parallel with the plane of the valve and spaced therefrom, the diameter of the annular portion being substantially equal to the diameter of the port, the margin of the annular portion being spaced from the valve for a distance substantially equal to the vertical depth of the port whereby the lip of the body is received in the port when the valve is closed and the valve and body are fixed with relation to each other, said body being provided with a plurality of relatively small closely spaced apertures.

In testimony whereof I hereunto affix my
signature.

EDGAR HEATON.
